DESIGN FOR A SLEEPING BAG

Maurice D. Frazee, Washington, D. C.

Application June 2, 1944, Serial No. 113,837

Term of patent 3½ years

(Cl. D92—2)

To all whom it may concern:

Be it known that I, Maurice D. Frazee, a citizen of the United States, residing at 1965 S Street, S. E., Washington 20, District of Columbia, have invented a new, original, and ornamental Design for a Sleeping Bag, of which the following is a specification, reference being had to the accompanying drawing, forming a part thereof.

Fig. 1 is a side elevational view of a sleeping bag, showing my new design.

Fig. 2 is a rear perspective view of the sleeping bag shown in Fig. 1; and

Fig. 3 is a perspective view thereof, with the suspender portion being shown partially broken away.

I claim:

The ornamental design for a sleeping bag, as shown.

MAURICE D. FRAZEE.
